UNITED STATES PATENT OFFICE.

WILLIAM HOLSTEIN, OF NEW YORK, N. Y.

DESIGN FOR A BUTTON, BADGE, PIN, OR ARTICLE OF SIMILAR NATURE.

53,268.

Specification for Design.

Patented May 6, 1919.

Application filed January 27, 1919. Serial No. 273,490. Term of patent 3½ years.

To all whom it may concern:

Be it known that I, WILLIAM HOLSTEIN, a citizen of the United States, and a resident of the city of New York, in the borough of Manhattan and State of New York, have invented and produced a certain new, original, and ornamental Design for a Button, Badge, Pin, or Article of Similar Nature, of which the following is a specification, reference being had to the accompanying drawings, forming part thereof.

The figure is a plan view of a button, badge, pin or the like, on an enlarged scale, showing my new design.

I claim:

The ornamental design for a button, badge, pin, or article of similar nature, as shown.

WILLIAM HOLSTEIN.
